UNITED STATES PATENT OFFICE

155,283

DESIGN FOR AN INDIRECT LIGHTING FIXTURE

Irol G. Gangbin, Fresno, Calif.

Application January 24, 1949, Serial No. 424

Term of patent 14 years

(Cl. D48—23)

To all whom it may concern:

Be it known that I, Irol G. Gangbin, a citizen of the United States, residing at Fresno, in the county of Fresno and State of California, have invented a new, original, and ornamental Design for an Indirect Lighting Fixture, of which the following is a specification, reference being had to the accompanying drawing, forming a part thereof.

Fig. 1 is an end elevational view of an indirect lighting fixture, showing my new design; the opposite end of the fixture presenting the same appearance.

Fig. 2 is a side elevational view of the indirect lighting fixture.

Fig. 3 is an enlarged cross sectional view of the indirect lighting fixture.

Fig. 4 is a perspective view of the indirect lighting fixture, looking underneath the same from one end.

The characteristic features of my design reside in the portions shown by means of full lines in the drawing.

I claim:

The ornamental design for an indirect lighting fixture, as shown and described.

IROL G. GANGBIN.
